SUPPORTING MEANS FOR RADIO COIL
UNITS AND THE LIKELouis H. Zepp, Philadelphia, Pa., assignor to Phil-
co Radio and Television Corporation, Philadel-
phia, Pa., a corporation of Delaware

Application October 16, 1941, Serial No. 415,329

4 Claims. (Cl. 74—424.8)

This invention relates to a novel supporting means for a device employing an adjustable element. An example of such a device is a radio coil unit having a screw-adjustable element for changing the electrical characteristics of the unit.

While the invention is capable of use for supporting objects generally, it is particularly directed to the support of coil units for modern radio receivers, such as intermediate frequency transformers, having a presettable element which may be adjusted for changing the tuning of the coil and associated units.

The principal object of the invention is to provide novel means for supporting and actuating a screw-adjustable element such as above-mentioned.

Another object of the invention is to provide a novel coil unit-supporting device which may be economically manufactured and readily assembled.

A further object of the invention is to provide a novel coil unit-supporting device made entirely of metal stampings.

The invention may be more clearly understood by reference to the accompanying drawing in which

Fig. 1 is a partial sectional view of a coil assembly embodying the present invention;

Fig. 2 is a detailed sectional view taken on line 2—2 of Fig. 1;

Fig. 3 is a perspective view of a principal part of the device of Fig. 1; and

Fig. 4 is a sectional view taken along line 4—4 of Fig. 2.

Referring particularly to Fig. 1 there is shown a portion of a metal coil shield container 1 within which a pair of coil units 2 and 3 are mounted on a fiber insulating plate 4. In Fig. 2 the coil winding 5 is shown on a tubular form or sleeve 6, which may be formed of cardboard, the coil being protected by a covering of wax 7. The base of sleeve 6 is provided with an inturned annular flange 8 as shown. The sleeve 6 is secured to the plate 4 by a stamped eyelet 9 having a body portion terminating at one end in an outwardly flanged head 10. To secure the eyelet 9 to sleeve 6, the latter preferably is formed with an annular recess or groove 11 in which the eyelet flange 10 may be seated as shown in Fig. 2. The assembly of sleeve 6 and eyelet 9 may be held to plate 4 by extending the eyelet through an opening in the plate and securing the assembly therein with any suitable fastening means such as a spring fastener 12 of conventional form.

As noted above the coil unit is of the type hav- 55

ing an adjustable element. This may be a core member 13 of comminuted iron slidably disposed in sleeve 6. A threaded adjusting screw 14 may be used to adjust the core 13 axially of sleeve 6 and coil winding 5. Screw 14 is attached to member 13 and extends through eyelet 9. In accordance with the present invention eyelet 9 is formed with an inturned lip 15 on the outer end of the body portion and extending over a portion of the circular end. This lip 15 is best illustrated in Figs. 2 and 3 from which it will be seen that the lip serves as a single screw thread which may be formed when the eyelet is stamped or which may be formed on a performed eyelet by obliquely striking the end thereof so as to shorten the axial length of the eyelet along one side to provide the desired inturned lip. Screw 14 is threadedly engaged with lip 15, and core 13 may thus be held in a preset position or may be adjusted axially of coil 5 by the adjustment of screw 14.

In the case of a multiple coil assembly, as illustrated in Fig. 1, two or more coil units may be secured to an insulating plate in the manner illustrated in Fig. 2. The coil assembly may then be placed within the coil shield container 1 with the screws 14, and in some cases the end portions of the eyelets 9, extending through openings in the container as illustrated. The coil assembly including plate 4 may be held in position relative to the container 1 by fastening means 16, each of which is preferably fastened on the associated screw 14 so as to lock the same against rotation in addition to securing the coil assembly within the container by providing a force longitudinally of the axis of the eyelet. One well known form of spring fastener having a detent 17 engaging the screw threads is illustrated in Figs. 2 and 4, and it is believed that the manner of assembling and locking the elements in place will be clear from the illustration.

From the foregoing it will be seen that the present invention provides a fastening device for coil units and the like so designed as to be adapted for economical manufacture and simple assembly, yet the device is entirely reliable and positive. An important advantage of the device is that it eliminates the necessity of providing internal threads on the element which is threadedly engaged with screw 14, and it enables the use of the simple stamped eyelet 9 as the said element. It will be understood, of course, that the invention is not limited to the specific form illustrated but is capable of modification within the scope of the appended claims.

I claim:

1. A device for supporting a tubular object having an adjustable member, comprising a metal stamping having a hollow elongated body portion secured to and extending axially outward from the tubular object, a mounting plate having an opening therein, the outwardly extending hollow body portion of said stamping extending through the mounting plate opening and constituting the sole support for said tubular object, a member engaging said stamping hollow body portion for attaching the stamping to said mounting plate to secure the tubular object thereto, an inturned lip at the outer end of said stamping body portion providing a screw thread, and screw means associated with said adjustable member extending through said stamping body portion and engaging said thread so that said adjustable member may be adjusted by rotation of said screw means.

2. A device for supporting a tubular object having an adjustable member in a container having an aperture therein, comprising a mounting plate having an aperture therein registering with the aperture of said container, a metal stamping having a hollow elongated body portion secured to and extending axially outward

5 from the tubular object through the apertures in the mounting plate and container, and constituting the sole support for said tubular object, an inturned lip at the outer end of said stamping body portion providing a screw thread, screw means associated with the adjustable member extending through said stamping body portion and engaging the inturned thread lip thereof, a member engaging said stamping hollow body portion for attaching said stamping to said mounting plate to secure said assembly thereto, and a fastener engaging said screw means to secure the same to said container and to lock the screw means against rotation.

10 3. A device as claimed in claim 1 wherein the metal stamping is secured to the tubular object by means of an out-turned flange on the inner end of the hollow body portion thereof which is interlocked with the adjacent end of said tubular object.

15 4. A device as claimed in claim 2 wherein the metal stamping is secured to the tubular object by means of an out-turned flange on the inner end of the hollow body portion thereof which is interlocked with the adjacent end of said tubular object.

20 LOUIS H. ZEPP.
